LOCK

Edgar Otto Julius Kelly, London, England, assignor to Newton, Lansdowne & Company Limited, London, England

Application August 6, 1946, Serial No. 688,630
In Great Britain August 20, 1945

6 Claims. (Cl. 70—227)

1

This invention relates to a lock device of the kind which incorporates a sliding bolt element adapted to be held in a locked position and releasable by a key. In particular the invention relates to a lock device which can be employed upon bicycles to lock the same against unauthorised use by the bolt element being locked in a position in which it is in the path of the spokes of one of the wheels of the bicycle (usually the rear wheel) so that the wheel cannot rotate.

The invention has for its object to provide a lock device which is efficient in operation and cannot readily be tampered with or removed.

A lock device in accordance with the invention comprises a casing which carries the sliding bolt member which forms the actual locking member and the release of which from a position in which the bolt is projected beyond one end of its casing into the locking position is controlled by a key which itself actuates lock mechanism contained within the casing, the sliding bolt member being resiliently biased into the open or retracted position and requiring to be set manually in the projected or locked position, from which it is only releasable by the insertion of a key, which latter is held retained upon the casing while the bolt is in the retracted and unlocked position.

The casing is formed in two parts telescoped one upon the other to form a completely enclosed casing which can only be opened when the bolt is unlocked and this only when the key is actuated to shift a finger member within the casing which normally holds the bolt against endwise movement and at the same time engages a plunger member which passes through the telescoped casing parts to secure the latter together and which cannot be moved endwise to permit separation of the casing parts unless the said finger is actuated by the key to remove same from locking engagement with the bolt and plunger members.

Thus the lock device comprises a hollow casing which is conveniently of box-like or rectangular shape and is formed in two parts having a telescopic fit with each other to form a completely enclosed casing and one of which casing parts carries a sliding bolt member, which forms the actual locking member and the release of which from a position in which the bolt is projected beyond one end of its casing part into the locking position is controlled by a key which itself actuates lock mechanism contained within the casing.

The said bolt member is conveniently in the form of a flat elongated bar which is slidable through slots in the opposite ends of the casing part in which it is contained and is located close-

2

ly adjacent to the inner end of the shallow casing part, when the latter is assembled upon the deeper casing part, and the portion of the latter which enters into the shallow casing part is also provided with slots in its end walls which are in register with corresponding slots in the outside end walls of the shallow casing part to provide for the sliding movement therethrough of a plunger member which must be removed endwise through these slots to permit the two casing parts to be separated but which removal cannot be effected when the locking bolt is in the locked position, the projection of the bolt into the locked position automatically locking this plunger against removal.

The invention also consists in a lock device having the further features hereinafter described and indicated.

In the accompanying drawings:

20 Figure 1 is an elevational view of one embodiment of the invention, showing the bolt, in the projected or locked position.

Figure 2 is a section on any of the lines A—A in Figures 1, 5, 6, 8 and 9,

25 Figure 3 is a sectional plan on the line B—B of Figure 2, with the bolt shown in the released condition.

Figure 4 is a sectional plan view on the line C—C of Figure 2, with the bolt in the released position as in Figure 3,

30 Figure 5 is a sectional plan on the line B—B of Figure 2 but showing the key in the position in which the bolt is ready to be unlocked.

Figure 6 is a sectional plan on the line C—C of Figure 2 showing the bolt in the locked position corresponding to the position of the parts as in Figure 5,

35 Figure 7 is a sectional plan on the line C—C of Figure 2 showing the two cover plates in the locked position of the bolt but with the bolt, spring and pivoted plate removed.

Figure 8 is a view similar to Figure 7 but showing also the pivoted plate in the position it occupies in the locked condition of the bolt.

40 Figure 9 is a plan view looking on the top end of the deeper casing part, with the shallow casing part removed, and

Figure 10 is an end elevation of Figure 1.

In carrying the invention into effect in one convenient manner a lock is provided, suitable for use as a bicycle lock, comprising a hollow casing which is conveniently of box-like or rectangular shape and is formed in two parts consisting of a deeper and major part which fits in a telescopic manner at the open end thereof into the open

end of a shallow casing part 1a and carries a sliding bolt member 2 which forms the actual locking member and the release of which from a position in which the bolt is projected beyond one end of its casing part into the locking position is controlled by a key 3 which itself actuates lock mechanism contained within the casing. In such unlocked position the key cannot be removed from the casing and thus loss of the key is avoided.

This bolt member 2 is conveniently in the form of a flat elongated bar which is slidable through slots 2b in the opposite ends of the casing part 1 and is located closely adjacent to the inner end of the shallow casing part, when the latter is assembled upon the deeper casing part. The portion 1b of the latter which enters into the shallow casing part is also provided with slots 4c in its end walls which are in register with corresponding slots 4d in the outside end walls of the shallow casing part to provide for the sliding movement therethrough of a plunger member 4 which must be removed endwise through these aligned slots 4c and 4d to permit the two casing parts to be separated but which removal cannot be effected when the locking bolt 2 is in the locked position, the projection of the bolt into the locked position automatically locking this plunger against removal.

The lock mechanism contained within the deeper casing part is entirely concealed within the latter and consists of a series of tumbler members 5 each spring loaded by a spring 6 and which tumbler members are disposed in parallel and closely adjacent relationship and are guided for sliding movement within channels 7, 7a, formed in part (the channel part 7) in one plate 8 and in part (the channel part 7a) in another plate 9 mounted within the deeper casing part so as to lie adjacent the inside of the closed end or bottom 10 thereof and which channels extend in a transverse direction so that they extend parallel with the end walls 11 of the casing.

In the description hereinafter the casing will be regarded as vertically disposed with the base of the deeper casing part 1 lowermost.

The one plate 8 (hereinafter referred to as the "bottom plate") is conveniently formed so as completely to cover the inside surface of the base of the deeper casing part and has its guide channels 7 formed to extend from one side edge thereof to an intermediate position with respect to the opposite side edge. The other said plate 9 (hereinafter referred to as the "top plate") is generally of L shape in plane (as shown in Figures 3 and 5) and is mounted immediately upon the bottom plate so that normally, and in the locked condition of the tumblers 5, as shown in Figure 5, upstanding parallel shallow flanges 12 extending transversely across the upper face of the longer limb 9a of the top plate are continuous with corresponding upstanding flanges 13 from that part of the face of the bottom plate which is not covered by said limb 9a of the top plate, these flanges 12 and 13 forming the guide channels above referred to and the outer ends of the latter on the top plate terminating in a straight line spaced from and parallel with the adjacent and outer longitudinal edge of the said limb 9a of the top plate, which limb of the latter has an upstanding longitudinal flange or rib 15 which extends alongside the said guide channel ends to close the latter and form an abutment against which the tumblers 5 are normally biased by the action of the springs 6. The inner ends of the guide channel portions 1a on the

top plate are also situated on a straight line, which extends parallel with the longitudinal edges of the plate and perpendicular to the direction of the guide channels. This line, which is indicated at 14 in Figures 3 and 5, is spaced somewhat from the inner longitudinal edge 9c of said limb of the top plate to define an edge portion 9b of the latter which is engaged beneath undercut portions of the inner ends of the flanges 13 on the bottom plate which inner ends of these flanges terminate also on the line 14, which forms a common dividing line between the channel portions 7 and 7a.

Each complete guide channel (of which there may be three, for example as shown in the drawings) contains a coil spring 6, a plunger 16 and a tumbler member proper 5 all arranged in line one behind the other in their respective channels with the spring located at one end of its guide channel in the end thereof contained on the bottom plate, the corresponding tumbler member being located at the opposite end of its guide channel and in the portion of the latter which is on the top plate and the plunger being located between its associated spring and tumbler member. Each of the latter has a pointed angular outer end 5a which is normally biased by the action of its spring into contact with the closed end of its guide channel formed by the aforesaid abutment 15 on the top plate while the outer end of each coil spring bears against that side wall 11a of the casing part which closes the outer ends of the guide channel portions on the bottom plate. The plungers, as stated, lie within their respective guide channels between their associated tumbler members and springs and the arrangement is such that in the normal and locked condition of these parts the plungers 16 extend across the dividing line 14 between the adjacent inner ends of the guide channel portions and prevent the top plate 9 from being displaced by a sliding movement thereof in a longitudinal direction upon the bottom plate, the top plate being permitted to partake of such sliding movement, in the unlocked condition of the parts, against the action of a spring 17, a central coiled portion 17a of which is mounted upon a pin 17b upstanding from the bottom plate 8 adjacent the outside of one of the outermost guide channel flanges on this plate and free end portions 17c and 17d of the spring engaging one (the portion 17c) with the outside of this flange 13 and the other (the spring portion 17d) with the inside vertical edge of an upstanding longitudinal flange 18 on an inwardly recessed part at one end of said limb 9a of the top plate. The other limb 9d of the latter, at the opposite end of the plate, extends along the outside of the other outside guide channel flange 12 on the bottom plate and terminates near the outer end of said guide channel flange in an upstanding longitudinal flange 19 while the outer edge of this limb 9d of the top plate, at the end thereof remote from said upstanding longitudinal flange 19, is formed with an upstanding transverse flange 20 which forms an abutment for the inner end of the key member 3. The latter has its main and body part constituted by a flat strip of metal or other suitable material which is capable of being passed into the deeper casing part 1 through a slot 3a, Figure 10, (hereinafter referred to as the "key entry slot") therein situated in the plane of the upper edge surfaces 12a of the guide forming flanges 12 on the top plate which lie on a lower plane than the remainder of the upper edge sur-

faces of the guide flanges which are joined to the said lower edge surfaces by vertical shallow in-steps 12b which are located in line with the inside longitudinal surface of the upstanding flange 18 on the said inwardly recessed part of one end of the top plate, whereby this surface of said flange 18 and the aforesaid steps 12b form a guide for the inner longitudinal edge 3b of the key, the outer longitudinal edge 3c of which is guided in its passage into the casing by the adjacent longitudinal wall 11b of the casing.

The body part of the key, along its inner longitudinal edge 3b, is formed with angular recesses 21 which are of varying depth and size and correspond with the tip portions of the angled or pointed ends 5a of the aforesaid tumblers 5, which latter are of varying lengths as shown. The inner end of the key is formed with an inclined edge portion 22 and the arrangement is such that when the key is passed into the slot 3a in the deeper casing part this inclined edge 22 by engagement with the leading inclined faces of the tumblers forces the tumblers, one after the other, inwards within their guide channels 7 against the action of their coil springs 6 so that the key is permitted to pass into the casing until its inner end is brought up against the said upstanding transverse flange or abutment 20 on the top plate 9. When this occurs the key will be so positioned within its guide slot (constituted by the flange 18 and steps 12b on one side and by the inside of the wall 11b of the deeper casing part on the other side) that the angular recesses 21 along its inner edge will be immediately opposite the pointed tips 5a of the tumbler members with which these recesses correspond and in this position the inner ends of the tumblers will, as shown in Figure 5, all be in a straight line which coincides with the dividing line 14 between the guide channels on the bottom plate and those on the top plate. The lock mechanism, therefore, is now ready to be unlocked in that further inward movement of the key, by the inner end thereof pressing against the abutment 20 on the top plate 9, will shift the latter bodily towards the end wall 11 of the casing remote from the key entry slot and this against the action of the spring 17, this spring serving normally to bias the top plate into a position in which the guide channel portions 7a thereon are in line with the guide channel portions 7 on the bottom plate 8.

All the lock mechanism just described is confined within the portion of the deeper casing part 1 immediately adjacent the base or closed end 10 thereof and is covered by a pair of co-planar plates 23 and 24 (Figures 2, 4, 6, 7 and 8) hereinafter referred to as "cover plates," which fit within the casing to lie alongside one another and each of which extends longitudinally over the said guide channels so as to cover the latter and the lock elements accommodated therein.

One said cover plate 23 is formed to extend over the channel portions 7a on the said top plate 9 and this cover plate, on its inner edge, is formed with a wider central portion 23a of an extent sufficient to extend across and cover the dividing line 14 between the two guide channel portions 7 and 7a.

The other cover plate 24 has a corresponding central recess 24a in its inner longitudinal edge into which recess the said wider central portion 23a of the other cover plate 23 extends and along its outer longitudinal edge, near the end thereof remote from the key entry slot 3a, the cover

plate 24 is also formed with a recess 25 through which the said upstanding and longitudinal flange 19 on the top plate 9 passes while at its opposite end this longitudinal outer edge of the cover plate 24 is formed with an upstanding longitudinal flange 26.

The cover plate 23 has a pair of upstanding posts 27 and 28, the former of which serves to receive the central coiled portion of a spring 29 adapted to co-operate with the sliding bolt 2 and referred to hereinafter as the "bolt spring" and the other of which posts 28 serves to form a pivot for yet another plate member 30 which is mounted upon the top of the said cover plates 23 and 24 and will be referred to hereinafter as the "pivoted plate," this pivoted plate 30 being pivotally mounted at one corner upon the said post 28.

The recess 24a in the inner longitudinal edge of the cover plate 24 is longer than the central wider portion 23a of the other cover plate 23 and in the locked condition of the parts of the lock mechanism, as shown in Figure 6, the former said cover plate 24 is so disposed that a gap 24b exists between that end of the recessed inner edged this cover plate which lies nearest to the key entry slot and the corresponding end of the wider portion of the former cover plate 23.

The pivoted plate 30 along its longitudinal edge adjacent the pivoted corner thereof is formed with an upstanding longitudinal flange or finger 31 (hereinafter referred to as a "finger") and along its opposite longitudinal edge and opposite the said pivoted corner the pivoted plate 30 is formed with a recess 32 in which the said upstanding longitudinal flange 26 on the outer longitudinal edge of the cover plate 24 engages.

The arrangement is such that when the inner end of the key 3 is pressed against the abutment flange 20 on the top plate 9 (and at which time the tumbler members 5 will be so positioned as to permit the top plate to be shifted) the longitudinal sliding movement of the top plate thereby produced will be accompanied by a corresponding movement of the cover plate 24 due to the engagement therewith of the upstanding flange 19 on the end of the transverse limb 9d of the top plate 9 and such movement of this last mentioned cover plate 24 will in turn be accompanied by an angular movement of the pivoted plate 30 due to the engagement of the upstanding flange 26 on the cover plate 24 with the recess 32 in the pivoted plate, which is thereby constrained to move about its pivot 28.

The pivotal movement of the pivoted plate 30 is relied upon to bring the finger 31 thereon into the path of the movement of the bolt 2 and the plunger 4, for which reason the latter are each formed with recesses 2a and 4a respectively along their longitudinal edges into which the finger 31 can enter when the pivoted plate is so moved and which finger 31 is of sufficient depth to extend upwardly through the recess 2a in the longitudinal edge of the bolt and also through the recess 4a in the longitudinal edge of the plunger. The recess 2a in the bolt 2 may be longer than the recess 4a in the plunger 4 and the finger 31 may be given a step formation, as indicated at 31a, to correspond, the longer step being at the bottom.

The bolt spring 29 has an end portion 29a which extends between a pair of upstanding pins 33 and 34 loosely fitted into longitudinally spaced holes in the surface of the bolt 2 and adapted to provide a bearing for this end 29a of the spring such that the latter tends to bias the bolt into the

7
retracted or unlocked position as shown in Figure 4.

The bolt 2 sits on top of the pivoted plate 30 so as to be slidable thereover and the bolt is itself covered by a closure plate 35 (Figure 9) which fills the openings to the deeper casing part 1 and has a hole 36 in its base through which the upper end of the finger 31 can project for engagement with the recess 4a in the longitudinal edge of the plunger 4, which latter is guided for endwise movement upon the top of this closure plate 35.

The shallow casing part 1a is fitted on the outside of its closed end with a saddle piece 37 adapted to pass over a retaining post, such as one of the members of a bicycle frame, and which saddle piece is secured to the outside of the casing part 1a by means of screws 38 the heads 38a of which are located on the inside of the casing part so that they are inaccessible from the outside for removal and are only accessible when this casing part is removed from the casing part 1.

The plunger 4 consists of a flat strip of metal capable of being passed through the aligned slots 4c and 4d in the telescoped casing parts and to extend across the entire length of the latter with the ends of the strip located in said slots. At one end, remote from the end near which the recess 4a for receiving the upper end of said finger 31 is provided, this strip is formed with a screw threaded hole 4b in which a screw (not shown) passed through the closed end of the shallow casing part may be engaged. This screw must be removed when it is desired to move the plunger strip endwise to separate the casing parts, which, as stated, can only be effected when the key 3 is actuated to hold the finger 31 out of engagement with the recesses 2a and 4a in the bolt and plunger members, the plunger member being conveniently provided with a recess 4a on its opposite longitudinal edges so that either recess can be engaged by the projecting upper end of the finger 31 depending upon which face of the plunger strip 4 is uppermost.

I claim:

1. A cycle locking device comprising a casing formed in two parts one of which is securable to the cycle frame by means manipulable from within said part, a locking bolt member slidably movable through the casing, a removable plunger member passing through both parts of the casing to secure them together, a finger member within the casing for locking the bolt member in its locking position and simultaneously engaging the plunger member to prevent its removal, and locking mechanism within the casing actuated by a key for withdrawing the finger member from engagement with both the bolt and plunger members to permit movement of the bolt member to its unlocking position and removal of the plunger member when it is desired to separate the casing parts.

2. A cycle locking device as claimed in claim 1,

8
wherein the locking mechanism includes a resiliently biased member having connecting means operatively connecting said biased member with the finger member, the bolt member being manually movable into its locking position in which said biased member, under the action of its resilient biasing means, effects movement of the finger member into position to lock the bolt member and to engage the plunger member.

10 3. A cycle locking device as claimed in claim 1, wherein the locking mechanism includes a resiliently biased member having connecting means operatively connecting the biased member with the finger member, said biased member being movable by the key against the action of its resilient biasing means to cause withdrawal of the finger member from engagement with both the bolt and plunger members.

15 4. A cycle locking device as claimed in claim 1, having a pivoted member within the casing carrying the finger member, an intermediate movable member within the casing operatively connected with the pivoted member, and a resiliently biased member within the casing operatively connected to the intermediate member, said biased member being movable by the key against the action of its resilient biasing means to cause withdrawal of the finger member from engagement with both the bolt and plunger members.

20 5. A cycle locking device as claimed in claim 1, wherein the locking mechanism comprises a series of two-part spring-loaded plungers guided in two-part channels, and a resiliently biased member carrying one part of each of the two-part channels and having connecting means operatively connecting said biased member with the finger member, the key, upon actuation of the locking mechanism, moving the plungers from a position in which they prevent relative movement 25 between the two parts of each channel to a position in which such relative movement may take place, and in which position the key may move said biased member against the action of its resilient biasing means to effect withdrawal of the finger member from engagement with both the bolt and plunger members.

30 6. A cycle locking device as claimed in claim 1, wherein the casing part secured to the cycle frame carries a saddle piece for connecting it to the frame, said saddle piece being secured to the casing part by means of screws, the heads of which, in the assembled position of the casing parts, are concealed within the casing.
